JOHN M. CLARK, OF DETROIT, MICHIGAN, ASSIGNOR TO THE UNIVERSAL BUTTON FASTENING & BUTTON CO., OF DETROIT, MICHIGAN, A CORPORATION OF MICHIGAN

FASTENER ATTACHING MACHINE

Application filed January 9, 1922, Serial No. 527,846. Renewed January 24, 1929.

This invention relates to machines for attaching articles and particularly to a button attaching or fastening machine. Among other objects the invention is intended to provide improved and reliable mechanism for automatically attaching buttons to fabrics and the like.

The invention consists in the novel constructions, combinations and arrangements, hereinafter described or claimed, for carrying out the above stated object and such other objects as may appear from the following description.

The invention is illustrated in a preferred embodiment in the accompanying drawings in which:

Fig. 1 is a side elevation of the machine.

Fig. 2 is an end elevation.

Fig. 3 is a vertical section through the button and fastener delivery mechanism.

Fig. 4 is a fragmentary horizontal section of the button receiver and button carrier taken along the line 4—4 of Fig. 3.

Fig. 5 is a plan view illustrating the button receiving mechanism in a different position and showing portions of the button carrier mechanism in dotted lines.

Fig. 6 is an elevation, certain parts being in section and certain parts being broken away, of the button supply means and the button raceway.

Fig. 7 is a vertical transverse section, somewhat enlarged, taken along the line 7—7 of Fig. 1.

Fig. 8 is a vertical, transverse section taken on the line 8—8 of Fig. 4 through the button delivery mechanism and the button raceway, the parts being somewhat enlarged.

Fig. 9 is a vertical, longitudinal section through the button delivery mechanism showing the button positioning device in one position.

Fig. 10 is a view similar to Fig. 9 but showing the button positioning fork with the prongs thereof straddling the bar of the button.

Fig. 11 is a perspective view of a portion of the machine and illustrating the button carrier and fastener raceway and related mechanism.

Fig. 12 is a vertical section along 12—12 of Fig. 5 and showing the button receiving mechanism.

Fig. 13 is a fragmentary, vertical section, somewhat enlarged, through the affixing and setting mechanism and taken along the line 13—13 of Fig. 1.

Fig. 14 is a view corresponding to Fig. 13, but showing the upper portion of the affixing and setting mechanism.

Fig. 15 is a fragmentary, vertical section corresponding to Figs. 13 and 14 and showing the setting mechanism in the position for setting the fastener around the bar of the button.

Fig. 16 is a plan view of the typical button adapted to be affixed by the mechanism illustrated and Fig. 17 is a cross-section taken along the line 17—17 of Fig. 16.

Like characters of reference designate like parts in the several figures of the drawings.

The particular machine illustrated as one embodiment of the invention is intended to supply buttons and fasteners, of the type hereinafter described, to fastener setting position and to attach automatically the button to fabric or the like by means of the fastener. The typical button is one having a transverse bar or equivalent member across the same for receiving the fastener. The typical fastener is one having a head and a pair of projecting prongs adapted to pierce the fabric and to be bent around the bar of the button to attach the latter to the fabric.

This machine comprises in general a suitable frame or supporting structure 10 upon which the various mechanisms and instrumentalities are arranged in convenient manner.

Buttons are supplied from button supply means 11 to a suitable button raceway 12 in such a way that the shanks or collets of the buttons all face in a certain direction. This may be accomplished by any suitable mechanism. That employed in the present machine comprises a rotary feed wheel 13 having a plurality of substantially radial slots or passages 14 corresponding in shape to the cross-section of the button and adapted to permit the passage of the button only when

the collet or shank thereof is turned outwardly so as to pass through the narrow portion of the slot, as illustrated in Figs. 2 and 6. The feed wheel rotates within a receptacle 15, 5 partly filled with buttons, in a clockwise direction as viewed in Fig. 6, and drops such buttons as are properly positioned in the passages 14 into the raceway, thus the buttons in the raceway 12 are arranged with the shanks or collets thereof all directed in one direction. The feed wheel 14 is periodically rotated through a shaft 16 by suitable ratchet mechanism. This mechanism may consist of a disc 17 having notches 18 therein 10 into which a spring detent 19 is adapted to snap. The rotation of the disc 17 is effected by means of a crank 20 and connecting rod 21 through any suitable ratchet mechanism 22. The same ratchet mechanism is adapted to 15 engage the spring 23 of the detent 19 to disengage it from notch 18 and permit the feed wheel to be rotated. The ratchet mechanism rotates the feed wheel through a third of a turn as illustrated. The speed of rotation is 20 sufficient to throw the buttons outwardly along the channels 14 by centrifugal force and to drop them into the raceway 12 through a suitable opening in the supply receptacle. The speed and frequency of the 25 periodic rotations is designed to supply sufficient buttons to the raceway for the needs of the machine.

Any other suitable button supply mechanism may be employed to supply buttons to 30 the raceway in the manner described.

The same shaft 16 also rotates a fastener feed wheel 24 within a fastener receptacle 25. The fastener feed wheel and receptacle are of conventional construction and need be only 35 briefly described. The fasteners are picked up by the curved portions 26 of the feed wheel, and those which straddle the same slide along the straight portion 27 of the feed wheel on to the raceway 28, when the rotation 40 of the feed wheel is arrested. The notches 18 in the disc 17 are so positioned as to arrest the feed wheel with one of the blades in the position shown in Fig. 1, so that the fasteners may slide upon the blade of the raceway 28.

Any other suitable means for supplying fasteners to the raceway may be employed.

The raceway or fastener conveyor means 28 comprises a blade or strip 29 adapted to 45 be straddled by the prongs of the fastener, and a guide member or rod 30 adapted to retain the fasteners in proper position upon the blade 29. The blade 29 is twisted through approximately 180 degrees, so that the fasteners received by it at one end are inverted or reversed until the points thereof are directed toward the setting mechanism, hereinafter described, when they reach the end of the raceway. The rod 30 is connected to 50 the blade 29 by connecting means 31 which

extend around the path traveled by the heads of the fasteners, and space the rod and blade a slight distance apart to provide a space for the heads of the fasteners. The rod 30 is so bent as to convey the fasteners in the 70 proper direction.

The lower end of the blade 29 of the raceway is inclined, as shown in Fig. 7, with respect to the end of the fastener passage 32. A pair of pivoted detents 33 or other suitable instrumentalities retain the fasteners on the race way and are adapted to permit the fasteners to drop one at a time into the mouth of the passage 32. The detents 33 75 may be operated in any suitable manner so that when one is withdrawn the other is presented to prevent the fasteners from running off the raceway. When the lower detent is withdrawn a fastener is dropped from the raceway and the upper detent is presented to hold the remaining fasteners upon the raceway. In the machine illustrated these detents are conveniently operated by a reciprocating member 34, having a suitable cam surface 34' thereon (see Fig. 4) for 80 withdrawing the lower detent and simultaneously permitting the other to be pressed forward by the aid of its spring 33', on the reverse movement of member 34, the lower detent is released and is moved forward by its spring and the upper detent is withdrawn. The arm of each detent is provided with a surface 33'' having a properly located, recessed cam surface to permit the detent to move forward at the proper moment. The detents and the particular mechanism for operating the detents are illustrative only and any other suitable means for dropping a fastener at the proper time may be employed. 85

The opening at the upper end of the fastener passage 32 is enlarged as shown at 90 in Fig. 7, and the blade of the raceway is so positioned relative thereto that when a fastener runs off the end of the blade one leg strikes against the surface 36 and the other leg is permitted to swing downwardly and enter the passage 32 in advance of the retarded leg. Thus, the fasteners as they are conveyed toward the setting mechanism are 95 rotated from the position they occupy upon the raceway to a position in which one prong or leg of the fastener is in advance of the other one in the passage 32. The lower portion of the passage 32 is enlarged as shown at 100 110 115 120 125 130 135 140 145 150 155 160 165 170 175 180 185 190 195 200 205 210 215 220 225 230 235 240 245 250 255 260 265 270 275 tener setting position. For this purpose the bottom of the passage 32 is provided with a slot at 40 for the slide 39. This slide is withdrawn far enough to permit each fastener, as it is dropped, to slide by gravity down the curved surface 38 into the horizontal portion of the passage 32.

The fastener delivery mechanism is operated by the main cam 41, having a cam groove 42 therein. The lever 43 pivoted to the frame of the machine at 44 is pivotally connected to the slide 39 by the link 45. This lever is provided with a cam roll 46 (see Fig. 1) running in the cam groove 42 by means of which the lever is oscillated to reciprocate the slide 39. The cam groove is designed so as to properly time the movements of the slide 39.

Opposite the end of the fastener passage 32 is a pair of fastener receiving jaws 47 between which the slide 39 is adapted to place a fastener. The faces of these jaws are provided with small notches 48 for receiving the advance prong or leg of the fastener and diverging faces 49 by means of which the jaws may be forced apart slightly as a fastener is placed between them. These jaws are pressed together by suitable leaf-springs 50 and are pivoted at their lower ends at 51, so as to be capable of swinging apart at the proper time.

The button raceway 12 is curved near its lower end so as to present the buttons in horizontal position with the shanks of the buttons down. (See Fig. 8.) Adjacent the end 35 of the raceway 12 is suitable button receiving mechanism adapted to receive one button at a time from the raceway and present it to the button delivery mechanism or button carrier hereinafter described.

40 The button receiving mechanism may conveniently comprise a housing or block 52 having therein a button receiving slide 53 which reciprocates past the end of the raceway 12. The slide 53 is provided with a channel or groove 54 of a size adapted to receive the shank or collet of the button when the former is in the position which it occupies in Fig. 4. The block 52 is provided with a stationary cam surface 55 adapted to be engaged by 50 the head of the button in the receiver or slide 53 as it moves rearwardly and which cams the button across the slide and passes it through the opening 56 in the block. (See Fig. 5). As the slide 53 moves to the left as 55 shown in Fig. 5, the end 57 thereof engages the foremost button in the race-way and retains the buttons in the race-way. When the button passes through the opening 56 from the button receiving mechanism it is presented to the button delivery mechanism hereinafter described. The reverse or forward movement of the slide 53 admits another button to the channel 54. The end 57 of the slide 60 is beveled as shown at 58 so that same may 65 pass under the heads of any buttons which

have become tilted in the race-way and bring them into proper position to pass upon the slide 53.

The button receiving mechanism is conveniently operated by a reciprocating member 59 having an elongated recess 60 therein for receiving a spring pressed detent 61 on the slide 53. The slide 53 is moved to the left when the end 62 of the recess 60 engages the detent but is not moved in the opposite direction until the end 63 of this recess comes in contact with the detent on the reverse movement on the reciprocating member 59. The forward surface of the detent is beveled as at 64 so that in the event the button receiving slide meets with excessive resistance in its rearward movement, the curved surface of the detent will serve as a cam and disengage it from operative connection with the member 59.

It may be noted in this connection that the member 59 also forms the actuating element of the button delivery mechanism referred to.

This button delivery mechanism comprises means for carrying a button from the receiving mechanism and delivering it to fastener affixing position and for rotating the button so that the bar thereof, when it is in fastener receiving position, occupies a definite relation to the prongs of the fastener intended to be fastened about the bar.

The illustrative button delivery mechanism comprises a reciprocating button carrier or slide which, in the construction shown, is attached to or forms a continuation of the reciprocating member 59 above referred to. The button carrier reciprocates through a housing 66 containing a button passage 67. The housing 66 may be conveniently included within the block 52 forming the housing for the button receiver. The end of the button carrier is cut away at 68 and 69 so as to receive a button. The button presented by the receiver to the button carrier is adapted to rest upon the surface 70 so that the off-set 68 engages the shank or collet of the button. The off-set 69 is cut back sufficiently far so as not to engage the head of the button. The surface 70 is provided with an opening 71 adapted to register with the opening or hole in the button. Pivoted between the slides of the carrier at 72 and in a space provided is a button positioning device 72 having an end or fork 73 adapted to enter the opening 71 and to straddle the bar of the button when said bar is in proper position. In this instance the fork is adapted to straddle the bar when the bar lies transversely to the direction of the button carrier. The fork 73 is pressed upwardly by a suitable spring 74 but is held depressed by the bar of the button on the carrier, as shown in Fig. 9, unless the bar is in proper position. The upward pressure of the fork against the bar of the button in the position as shown in Fig. 9 is resisted by 130

the pressure of the head of the button against the top of the passage 67. The housing surrounding the button carrier is provided with a cam groove 75 adapted to engage, at its 5 ends 76, a cam 77 on the button positioning device. In other words, when the button carrier reaches the limit of its travel in either direction, the cam surfaces 76 act to depress the button positioning device and withdraw 10 the fork 73 so that it does not project above the surface 70.

When the button carrier is drawn to the left as in Fig. 5, it is in position to receive a button from the button receiver slide 53 as 15 the latter passes a button through the opening 56. In this position the fork 73 is below the surface 70 and the button slides upon the carrier with the opening thereof substantially registering with the opening 71 as 20 shown in Figs. 9 and 10.

The button passage 67 is provided with a groove or channel 78 at the bottom thereof along which the button carrier slides. The upper portion of the passage is enlarged to 25 permit the passage of the head of the button. Along one side this passage is a friction device such as a leaf-spring 79 adapted to bear against the head of the button and press the same against the opposite wall of the passage. This opposite wall is so shaped as to 30 engage the shank only of the button. For this purpose the wall is extended at 80, engaging the shank of the button and leaving a slight clearance between the head of the 35 button and this side of the passage. The leaf-spring 79 is conveniently secured to the housing for the carrier and extends along the passage 67, so as to lightly engage the head of the button substantially throughout 40 its travel through the passage. The frictional engagements of the spring 79 against the head of the button and the surface 80 against the shank or collet of the button mutually oppose each other, intending to rotate 45 the button but since the spring 79 engages the button at a greater distance from the axis thereof than does the surface 80, it exerts the greater turning moment upon the button. This differential turning moment results in 50 the rotation of the button in a clockwise direction looking down upon it as in Fig. 4. While the pressure of the button against the off-set 68 on the button carrier also resists the rotation thereof, this pressure occurs so 55 close to the axis of the rotation that it cannot effectively prevent the rotation of the button. Therefore, as the button carrier moves forward with a button, the latter is rotated until the bar thereof occupies a position 60 transverse to the direction of the movement of the carrier at which time the fork 73 of the positioning device straddles the bar and arrests further rotation of the button. In the event that the button should be presented 65 from the receiver to the carrier with the bar

already in proper position, the fork 73 would at once straddle the bar of the button as soon as the carrier moved forward, thus locking the button against further rotation. The button passage 67 is made sufficiently long so that the button will be rotated through a sufficient angle in travelling through it to result always in the positioning of the bar in proper position.

With the bar in the proper position the 75 button is presented to button holding means 81. The button holding means may conveniently comprise a pair of spring jaws 82 having grooved engaging faces 83 adapted to frictionally hold the button when it is forced between the jaws by the button carrier. (See Fig. 13.) In this position the forward cam surface 76 causes the fork 73 to be withdrawn from its engagement with the bar of the button, so as to permit the button carrier to be 80 withdrawn, leaving the button in the jaws with the bar in proper position. The cam surface 76 is so designed as not to permit the fork 73 to rise until the carrier has been withdrawn a sufficient distance so as not to interfere with the button in the holding means. 90

The member 59 constituting the operating member for the button carrier, is provided at its rear end with an offset surface 84 to which is secured a leaf spring 85. The leaf spring 95 is spaced from the member 59 through the major portion of its length, but near its end is provided with a shoulder 86 and an offset portion 87 which presses against the member 59. Within the elongated space 88 thus provided, a reciprocating projection 90 is adapted to slide. The projection 90 is a portion of member 91 secured to the reciprocating fastener slide 39. When the projection 90 travels a sufficient distance to the left. (see 100 Fig. 4) it engages the offset 84 and withdraws the button carrier to the left. On the reverse travel of the slide 39 the projection 90 moves in the space 88 without transmitting a corresponding movement to the member 59 until it engages the shoulder 86 on the spring 85, at which time, the button carrier is moved 105 to the right and performs the functions described above. In the event that the button carrier or the button receiver meet with excessive resistance to their forward travel, the spring 85 would be forced outwardly, permitting the projection 90 to continue its travel, operatively disconnected from the member 59. This safety mechanism is provided in order to prevent breakage in the event an improperly shaped or positioned button should become jammed in either of the mechanisms referred to. 110

The fastener and button delivery mechanism are so co-ordinated as to present a fastener and a button respectively to setting position at about the same period in the cycle of operation, the setting position referred to being the positions occupied by the fasten- 115 120 125 130

er and button in their respective holding jaws (see Figs. 1 and 13). The setting mechanism comprises generally means for bringing the fastener and button together on opposite sides of a piece of fabric or the like and means for setting the points or prongs of the fastener around the bar of the button in this position. This mechanism may conveniently comprise upper die mechanism 93 and lower die mechanism 94 adapted to move relatively to each other during the setting operation. The upper die mechanism comprises a stationary housing or sleeve 95 having therein a reciprocating spindle sleeve 96 within which is mounted the spindle or setting tool 97. Between the ends of the setting tool and the sleeve 96 is a compression spring 98 tending to force the sleeve and die spindle 97 apart.

20 The upper end of the sleeve 96 is closed by screw plug 99 against which this spring presses. A suitable shoulder 100 on the die member 97 prevents the spring 98 from forcing the die member 97 entirely out of the sleeve. Operatively connected with the reciprocating sleeve 96 is a spindle lever 101 pivoted at 102 to the frame of the machine. The rear end 103 of the spindle lever 101 is operated by a suitable cam groove in the main cam 41. The opposite end 104 is, as stated above, operatively connected with the spindle sleeve 96 and is adapted to reciprocate the latter, thus reciprocating the die spindle 97.

Pivoted at 105 to the base of the machine 35 is a lever 106 operatively connected with the lower die spindle 107. The inner end of lever 106 is provided with a cam roll 106' which is pressed against the periphery of the main cam 41 by a spring 108. The rotation of the main cam causes the outer end of the lever 106 to raise and lower the lower die 107 at the proper time as hereinafter described. The outer end of lever 106 is provided with a handle 109 by means of which the lower die 40 45 107 may be raised by hand in the event it should be necessary to eject a defective fastener from the fastener jaws 47.

Surrounding the upper end of the spindle sleeve 96 is a collar 110 to which the spring 50 jaws 82 are secured at 111. The lower edge of the collar 110 is provided with a spring ring 112 which frictionally engages the spindle sleeve 96. As the spindle sleeve descends it carries the jaws 82, through the frictional action of the ring 112, downwardly until the ring strikes the upper end 113 of the stationary housing or sleeve 95. This engagement arrests the downward travel of the jaws and permits the die spindle to travel downwardly 55 60 relative thereto for the purpose hereinafter described.

The movements of the upper and lower setting mechanisms are so co-ordinated that after each has received its button and fastener, respectively, they are caused to travel to-

ward each other by the levers 101 and 106 respectively. The downward travel of the spindle sleeve 96 carries the button 114 toward the fabric 115 or other material to which it is desired to affix a button. When the button is thus brought into proximity with the fabric and the fastener, the ring 112 referred to strikes the upper end of the stationary casing 95 and arrests the travel of the jaws 82, permitting the die spindle 97 to travel downwardly relative thereto and to eject the button from the jaws. The resilient character of the jaw arms 82 permits this action. At about the same time the lever 106 raises the lower die 107 and brings the upper end thereof into contact with the cam surfaces 116 on the fastener jaws 47. This movement forces these jaws apart and permits the fastener to be raised above the same and forced through the fabric. The prongs of the fastener pass around the bar of the button, the bar having previously been placed in proper position relative to these prongs as described above, and engage the curved surface of the upper die 117, which has in the meanwhile ejected the button from its holding means. The die 117 turns the prongs of the fastener around the bar as shown in Fig. 15. The spring 98 yields when the setting of the prongs is completed, to prevent damage to the setting mechanisms by their continued movement toward each other.

Further rotation of the main cam 41 causes the upper and lower die setting mechanisms to separate and permits the removal of the fabric to which a button has been attached.

The upward travel of the spindle sleeve 96 raises the jaws 82 until the lower ends of the latter engage the lower end 118 of the housing 95. This arrests the further upward travel of the jaws in proper position to receive another button. The upward travel of the spindle sleeve continues until the die 117 is raised above the jaws.

Suitable mechanism for operating the machine to affix a button whenever desired is provided. This mechanism may consist of a driving pulley 119 rotated by a belt 120. The driving pulley 119 is loosely mounted upon the shaft 121 to which the main cam 41 is secured. A clutch 122 is provided by means of which the driving pulley may be operatively connected with the shaft 121 to rotate the latter when desired. The clutch is controlled by clutch pedal 123 connected by a rod 124 to a bell crank which normally engages the clutch and releases it. The clutch is of a type which is normally held in operative engagement by springs, but which may be disengaged whenever desired by arresting its rotation. For this purpose the clutch ring is provided with a stop 126 adapted to be engaged by the end 127 of the bell crank lever and be held against rotation. When the clutch pedal 123 is depressed, the end 127 of 130

the bell crank lever is withdrawn from engagement with the stop 126 on the clutch ring, whereupon the clutch becomes operatively engaged with the shaft 121. A spring 128 normally holds the bell crank lever in engagement with the stop 126 so that by removing pressure from the clutch pedal 123 the operation of the machine is automatically stopped. The particular mechanism above described, for effecting the operation of the machine whenever desired, forms no part of this invention. Any other suitable mechanism for controlling the machine may be used in place thereof.

Obviously, the invention is not limited to the details of construction of the illustrative machine, but may be variously modified. Moreover, it is not indispensable that all features of the invention be used conjointly; they may be employed advantageously in various different combinations and sub-combinations.

Having thus described my invention, I claim:

1. In a machine for attaching a button of the type described, the combination with attaching mechanism, of mechanism for feeding a button to the attaching mechanism, means for exerting friction on opposite sides of said button at different distances from its axis as it is fed forward whereby to rotate said button, and a device for arresting the rotation of said button when the same is in proper relation for receiving a fastener.

2. In a machine for attaching a button of the type described, the combination with attaching mechanism, of mechanism for feeding a button to the attaching mechanism, means for exerting a differential friction upon said button whereby to rotate the same as it is fed to the attaching mechanism, and a device for arresting the rotation of said button when the same is in proper relation for receiving a fastener.

3. In a machine for attaching a button of the type described, the combination with attaching mechanism, of mechanism for feeding a button to the attaching mechanism, means for exerting differential friction upon said button whereby to rotate the same as it is fed to the attaching mechanism, and a device for locking said button against rotation when the button is in proper relation to a fastener to receive the latter.

4. In apparatus of the class described, the combination with means for supplying buttons or the like and button affixing mechanism, of mechanism for transferring the button from the supply means to the affixing mechanism comprising a button carrier, and means bearing on opposite sides of a button at different distances from its axis for rotating the same as it travels with said carrier.

5. In apparatus for affixing buttons of the type described, button transferring mechanism comprising in combination a reciprocating

button carrier, and means for frictionally engaging a button on opposite sides thereof, but at different distances from its axis of rotation whereby to rotate the same as it is moved by said carrier.

6. In apparatus for affixing buttons of the type described, button delivery mechanism comprising in combination a reciprocating button carrier and means for frictionally engaging a button on opposite sides thereof, but at different distances from its axis of rotation whereby to rotate the same as it is moved by said carrier, and means for arresting the rotation of said button when it occupies a definite relation to said carrier.

7. In apparatus for affixing buttons of the type described, a button delivery device comprising in combination a button channel engaging the head of a button on one side and the shank thereof on the other, means for moving the button along the channel, and a device to arrest the rotation of the button when it occupies a definite position.

8. In apparatus for affixing buttons of the type described, a button delivery device comprising in combination a button channel, a spring in said channel for engaging the head of a button and pressing the shank thereof against the opposite side of said channel, a reciprocating slide for moving the button along the channel, and a device for entering a hole in the button to arrest its rotation when it occupies a definite position.

9. In apparatus for affixing buttons or the like, button delivery mechanism comprising in combination, a reciprocating button carrier, a position device on said carrier pressing against the button and adapted to enter an opening in the button when it occupies a definite position, means for rotating said button as it is moved by the carrier, and means for withdrawing said positioning device from the opening in the button when the latter is in affixing position.

10. In apparatus for affixing buttons or the like, button delivery mechanism comprising in combination a reciprocating button carrier, a member having a passage shaped to permit the passage of a button and having means for engaging the shank of the button on one side and for engaging the head of the button on the other side, and a positioning device on said carrier adapted to enter a hole in the button when it occupies a definite position and provided with means for pressing it against the button, said passage provided with a cam surface for withdrawing said device from the hole in the button after the button has traveled through said passage.

11. In apparatus for affixing buttons having a transverse bar across the opening therein, a button carrier having an opening therein adapted to register with the opening in the button, a positioning fork in the carrier open-

ing and pivoted to said carrier and adapted to enter the opening in the button to straddle the bar in said button when it occupies a definite position, and a spring for pressing 5 said fork against said button.

12. In apparatus of the class described, button delivery mechanism comprising in combination a button carrier, means for supplying buttons to said carrier, means for 10 moving said carrier so as to deliver a button to affixing position, and safety means for operatively disconnecting said moving means from said carrier whenever said carrier meets excessive resistance to movement.

13. In apparatus of the class described, button delivery mechanism comprising in combination a slidable button carrier, a reciprocating member for moving said carrier, and a resilient device on said carrier having 20 a shoulder adapted to be engaged by said member for moving the carrier, said resilient device adapted to yield when said carrier meets excessive resistance to movement to disengage said member from said shoulder.

14. In apparatus of the class described, button delivery mechanism comprising in combination a member having a button passage therein, means for moving a button through the passage, and a spring in said passage adapted to press said button against one wall of said passage, said passage being so shaped and the spring so positioned that the head of the button is engaged on one side of said passage and the shank on the other 35 whereby said button is rotated as it moves through said passage.

15. In a machine for affixing fasteners having a pair of spaced prongs, the combination of fastener conveying means adapted 40 to present the fasteners with the prongs side by side, and a fastener delivery member having a passage therein adapted to carry the fasteners arranged with one prong in front of the other, the end of said passage being 45 enlarged and said conveying means arranged with respect to said enlarged passage to direct said fasteners so that one prong strikes the wall of said enlarged passage and thereby rotates the fasteners so that the prongs 50 are positioned one in advance of the other.

16. In a machine for affixing fasteners having a pair of spaced prongs, the combination of fastener conveying means adapted to present the fasteners with the prongs side by side and a fastener delivery member having a passage therein adapted to carry the fasteners arranged with one prong in front of the other, the end of said passage being enlarged and said conveying means arranged with respect to said passage to direct said fasteners at an angle to the direction of said passage so that the fasteners are turned to enter the passage with one prong in advance 65 of the other.

17. In a button affixing machine, a button supply means, button delivery mechanism, and means for presenting buttons one at a time to said delivery mechanism comprising a movable member co-operating with said 70 supply means and adapted to receive a single button, and a cam surface stationary relative to said member and adapted to co-operate with said movable member to cam a button from the latter and present it to said 75 delivery mechanism.

18. In a button affixing machine, a button supply means, button delivery mechanism, and means for presenting buttons one at a time to said delivery mechanism, comprising 80 a slidable button receiver co-operating with said supply means to receive a single button and to prevent escape of buttons from said supply means, and a stationary cam surface adapted to be engaged by the button on the 85 receiver and so arranged as to cam the button laterally of the receiver during the movement thereof and to present the button to the delivery mechanism.

19. In a button affixing machine, button supply means, button delivery mechanism, and means for presenting buttons one at a time to said delivery mechanism comprising a movable member co-operating with said supply means and adapted to receive a single 90 button, a cam surface stationary relative to said member and adapted to co-operate with said movable member to cam a button from the latter and present it to said 95 delivery mechanism, means for moving said member, and a safety device for disconnecting said moving means from said member when the latter meets excessive resistance to movement.

20. In a button affixing machine, a button supply means, button delivery mechanism, and means for presenting buttons one at a time to said delivery mechanism comprising a slidable button receiver co-operating with said supply means to receive a single button and to prevent escape of buttons from said supply means, a stationary cam surface adapted to be engaged by the button on the 100 receiver and so arranged as to cam the button laterally of the receiver during the movement thereof and to present the button to the delivery mechanism, means for reciprocating said receiver, and a spring controlled 105 safety device for disconnecting said moving means from said receiver when the latter meets excessive resistance to movement during its forward stroke.

21. In a button affixing machine, the combination with fastener affixing and setting mechanism comprising an upper setting tool, 110 of button holding means frictionally engaged with said setting mechanism for holding a button directly below said setting tool and adapted to move with said tool, and a stop 115 for arresting the movement of said holding 120 tool.

means relative to said tool whereby the latter ejects the button from said holding means during the setting operation.

22. In a fastener attaching machine, the combination of a machine base having a pair of fastener holding jaws hinged thereto, a die member located between said jaws and operating upon a fastener held by said jaws, means for raising said die member in the operation of said machine for attaching the fastener, and a single manually operable means constructed and arranged to open both jaws independently of the operation of said machine so as to release a fastener from the grasp of said jaws.

23. A button attaching machine comprising in combination, attaching mechanism including means for holding a button and fastener in spaced relation to permit a web of cloth or the like to be interposed, means for feeding a fastener to said holding means, a carrier for supporting and moving a button to said holding means, means for operating said carrier, means for adjusting the button to a predetermined position relative to the fastener while it is being moved by said carrier, and means for actuating said attaching mechanism and holding means to bring the adjusted button and fastener together and to unite them.

24. A button attaching machine comprising in combination, mechanism for attaching a button to a web of cloth or the like by means of a fastener and having means whereby said web may be positioned to receive a button at any desired point, a carrier for supporting and moving a button to said attaching mechanism, means for rotating the button about its axis to a predetermined position while the button is being moved by the carrier to the attaching mechanism, means for feeding a fastener to said attaching mechanism, and means for actuating said attaching mechanism to bring said button and fastener together and to unite them.

25. A button attaching machine comprising in combination, button and fastener attaching mechanism including means for receiving a button in operative relation to the attaching mechanism, fastener supply means, button supply means containing a plurality of buttons in juxtaposition, a reciprocating carrier for supporting and moving successive single buttons to said receiving means, a device for transferring successive single buttons from said supply means to said carrier, means for operating said device and said carrier synchronously so as to effect the delivery of successive single buttons from said supply means to said receiving means, and means for actuating said attaching mechanism to unite a button and fastener.

26. A button attaching machine comprising in combination, button and fastener attaching mechanism including means for re-

ceiving a button in operative relation to the attaching mechanism, fastener supply means, button supply means containing a plurality of buttons in juxtaposition, a reciprocating carrier for supporting and moving successive single buttons to said receiving means, a transferring slide for receiving a single button from said button supply means and transferring the same positively to said carrier and means for operating said slide and said carrier synchronously so as to effect the delivery of successive single buttons from said supply means to said receiving means, and means for actuating said attaching mechanism to unite a button and fastener.

27. A button attaching machine comprising in combination, attaching mechanism including means for holding a button and fastener in spaced relation to permit a web of cloth or the like to be interposed, means for feeding a fastener to said holding means, a carrier for moving a button to said holding means, means associated with said carrier for rotating the button about its axis while the button is being moved by the carrier to the attaching mechanism, and a cooperating device for entering the central depression of the button when it has been rotated to a predetermined position whereby the button may be placed in said holding means in a predetermined position, means for operating said carrier, and means for actuating said attaching mechanism to bring the adjusted button and fastener together and to unite them.

28. A button attaching machine comprising in combination, attaching mechanism for uniting a button and a fastener, means for feeding a fastener to said attaching mechanism, a carrier for moving a button to attaching position, a device moving with said carrier having a projecting head constructed and arranged to project into the central recess of the button on the carrier, said head being of less height than the depth of the button so that it does not extend to the opposite face of the button, and means for moving said carrier and head to attaching position whereby the button is accurately placed in attaching position.

29. A button attaching machine comprising in combination, attaching mechanism for uniting a button and a fastener, means for feeding a fastener to said attaching mechanism, a carrier for moving a button to attaching position, and means associated with said carrier for rotating the button thereon about its own axis to a predetermined position while the carrier moves the button to attaching position, said means including a projecting head of less height than the depth of the button and constructed and arranged to enter the central recess of the button.

30. In a button attaching machine, the combination of means for attaching a tack and

button to a piece of fabric, means for injecting one of said members to said attaching means, feeding means, and means carried by said injecting means for detaching one of the members being fed from the feeding means and positively injecting the same to the injecting means.

31. In a button attaching machine, the combination of means for attaching a tack and button to a piece of fabric, means for injecting one of said members into said attaching means, feeding means, and means carried by said injecting means for detaching one of the members being fed from the feeding means and positively injecting the same to the injecting means at a point remote from the said attaching means.

32. An attaching machine of the character described comprising in combination attaching mechanism for uniting button and fastener elements, reciprocating slides carrying devices for engaging and for moving button and fastener elements respectively to said attaching mechanism, means for operatively connecting said slides for synchronous operation, and means for automatically actuating said slides to move successive button and fastener elements to said attaching mechanism.

33. A button attaching machine comprising in combination a machine base, attaching mechanism including upper and lower dies normally separated but relatively movable to attach a button with a fastener, said mechanism being carried by a housing which projects in front of said base, button and fastener slides respectively carried by said base and housing on a level with the extremities of the upper and lower dies respectively when in separated position, said slides being located in the vertical plane of said dies and adapted to move a button and fastener forward from said base to the upper and lower dies respectively, button and fastener raceways terminating adjacent the button and fastener slides respectively at points to the rear of said attaching mechanism, and means for placing single buttons and fasteners in front of the button and fastener slides, respectively, to be moved thereby to the respective attaching dies, a movable button holder associated with one of said dies and normally in alinement with the button slide for receiving a button therefrom and movable with said die away from said slide during the attaching operation, and a reciprocating device operatively connected with said slides for operating them synchronously.

34. A button attaching machine comprising in combination, attaching mechanism for uniting a button and a fastener, means for supplying a fastener, an oscillating device for moving a button to attaching position, means associated with said device adapted to rotate the button as it is being moved to

attaching position, and another device for controlling the amount of rotation of the button in order to adjust the button to a predetermined position.

35. A button attaching machine comprising in combination, attaching mechanism for uniting a button and a fastener, means for supplying a fastener, mechanism for moving a button to attaching position including means for rotating the button as it is being moved, and a device associated with said mechanism for entering the central recess of said button to control the rotation thereof in order to adjust the button to a predetermined position.

36. In a button attaching machine, the combination comprising, button attaching dies, a reciprocating slide having means for operatively engaging a button and moving the same to attaching position, a reciprocating member for positively actuating said slide in synchronism with the operation of said dies, guiding means for said member, and means between said member and said slide adapted to yield in the event said slide meets excessive resistance during the button moving operation to operatively disconnect said member from said slide.

37. A button attaching machine comprising in combination a machine base, attaching mechanism including upper and lower dies normally separated but relatively movable to attach a button with a fastener, said mechanism being carried by a housing which projects in front of said base, button and fastener slides respectively carried by said base and housing on a level with the extremities of the upper and lower dies respectively when in separated position, said slides being located in the vertical plane of said dies and adapted to move a button and fastener forward from said base to the upper and lower dies respectively, button and fastener raceways terminating adjacent the button and fastener slides respectively at points to the rear of said attaching mechanism, a transferring member interposed between the button raceway and the button slide for transferring a button from said raceway to a position in front of said slide, means for holding the button and fastener in operative relation relative to the respective dies, a reciprocating carrier in said base by which said slides are operated, guides for said carrier, and means actuated by said carrier for positively moving said transferring member.

38. An attaching machine of the character described comprising in combination attaching mechanism for uniting button and fastener elements, a delivery device for placing an element in attaching position, a raceway for holding a column of elements, an oscillating transferring device at the discharge end of said raceway and having a recess for receiving an element to move said

element to said delivery device, and a device for positively moving said transferring device both on its active and return travel in synchronism with said delivery device.

- 5 39. An attaching machine of the character comprising in combination attaching mechanism for uniting button and fastener elements, a reciprocating slide for delivering an element to said attaching mechanism, supply
- 10 means for furnishing a succession of elements, a reciprocating transferring device operated by said slide and having means for removing an element from said supply means, and cam means associated therewith
- 15 for positively moving said element to said delivery means.

In testimony whereof, I have signed my name to this specification.

JOHN M. CLARK.
